UNITED STATES PATENT OFFICE.

WILLIAM K. JONES, OF WICHITA, KANSAS.

INFANT'S APPAREL.

1,195,682.

Specification of Letters Patent. Patented Aug. 22, 1916.

Application filed July 8, 1915. Serial No. 38,734. ~~PENDING~~

To all whom it may concern:

Be it known that I, WILLIAM K. JONES, a citizen of the United States, residing at Wichita, in the county of Sedgwick and 5 State of Kansas, have invented certain new and useful Improvements in Infants' Apparel, of which the following is a specification, reference being had to the accompanying drawings.

10 This invention relates to certain improvements in infants' apparel; and it is an object of the invention to provide a novel and improved means whereby shoulder suspension may be afforded to a nether garment.

15 Furthermore, it is an object of the invention to provide a novel and improved device of this general character especially designed and adapted for use in connection with young infants and affording a means where- 20 by proper warmth may be afforded to the trunk of the body.

The invention consists in the details of construction and in the combination and arrangement of the several parts of my im- 25 proved infants' apparel whereby certain im- portant advantages are attained and the device is rendered simpler, less expensive and otherwise more convenient and advan- tageous for use, all as will be hereinafter 30 more fully set forth.

The novel features of the invention will be carefully defined in the appended claims.

In order that my invention may be the better understood, I will now proceed to de- 35 scribe the same with reference to the accom- panying drawings, wherein—

Figure 1 is a view in front elevation of one embodiment of my invention as herein set forth; Fig. 2 is a rear elevational view 40 of my invention as disclosed in Fig. 1; Fig. 3 is a plan view of the reinforcing member as herein embodied.

As disclosed in Figs. 1 to 3, 1 denotes a body garment of a type generally worn by 45 young infants and having its skirt portion 2 returned to afford a double thickness so as to assure maintaining the abdomen and back of the infant warm. The garment as disclosed in these figures is of a coat type 50 with the major portion of the opening 3 to one side of the neck of the garment and with the upper extremity 4 of said opening inclined toward the neck and in communication therewith. I also find it of advantage 55 to provide the skirt of the garment both in the front and in the rear with the vertically

disposed pairs of openings 5 through which the attaching member of a safety pin or the like may be passed so that the nether garments may be properly supported with a 60 possibility of injury to the body garment substantially entirely eliminated, and by having the openings arranged in vertically disposed pairs it will be perceived that an adjustable connection between the nether 65 garments and the body garment may be ef- fected as best meets the requirements of practice.

In order to relieve the neck of the wearer from strain, incident to the weight of the 70 nether garment, I find it particularly ad- vantageous to provide the garment 1 with the strips 6, the intermediate portion of which being longitudinally divided, as at 7, so that the strip may be disposed over the 75 shoulders of the garment at opposite sides of the neck with the opposite extremities 8 of the strip lying against the front and back of the shirt in alinement with the neck portion thereof.

In view of the foregoing, it is thought to be evident that the durability and length of wear of an under garment constructed in accordance with an embodiment of my invention is greatly prolonged and that the re- 85 inforcing strips serve to place the pull or strain of the garment on the shoulders.

From the foregoing description, it is thought to be obvious that infants' apparel constructed in accordance with my inven- 90 tion is of an extremely simple and compara- tively inexpensive nature and is particu- larly well adapted for use by reason of the convenience and facility with which it may be assembled, and it will also be obvious 95 that my invention is susceptible of some change and modification without material departure from the principles and spirit thereof and for this reason I do not wish to be understood as limiting myself to the 100 precise arrangement and formation of the several parts herein shown in carrying out my invention in practice.

I claim:

1. As a new article of manufacture, a 105 body garment of a coat type, the major por- tion of the opening being to one side of the neck of the opening and with the upper ex- tremity of said opening inclined toward the neck and in communication therewith, the 110 skirt portion of the garment being returned to afford a double thickness, and a reinforc-

- ing strip secured to the garment extending substantially the entire length of the front and back of the garment and overlying the doubled portion of the skirt at the front and 5 rear of the garment, the intermediate portion of the strip being longitudinally divided to permit the strip to be disposed over the shoulders of the garment at opposite sides of the neck, the front end portion of 10 the strip being disposed to one side of the opening, the opposite end portions of the strip being provided with longitudinally spaced pairs of openings.
2. As a new article of manufacture, a 15 body garment having its skirt portion of doubled thickness and a reinforcing strip secured to the garment and disposed over the shoulders thereof and extending substantially the entire length of the front and 20 back of the garment, and overlying the doubled portion of the skirt at the front and rear of the garment, the intermediate portion of the strip being longitudinally divided to permit the strip to be disposed over

the shoulders of the garment at opposite 25 sides of the neck.

3. As a new article of manufacture, a body garment having its skirt portion of doubled thickness, and a reinforcing strip arranged transversely of the doubled portion 30 and vertically of the garment and secured to the garment at the front and back thereof.

4. As a new article of manufacture, a body garment having its skirt portion of doubled thickness, and a reinforcing strip secured to the garment and disposed over a shoulder thereof and extending substantially the entire length of the front and back 35 of the garment, and overlying the doubled portion of the skirt at the front and rear of the garment.

In testimony whereof I hereunto affix my signature in the presence of two witnesses.

WILLIAM K. JONES.
